CLAIM

The ornamental design for an archery bow cam, as shown and described.

DESCRIPTION

FIG. 1 is a perspective view of the archery bow cam from an upper angle.

FIG. 2 is a first side view of the archery bow cam.

FIG. 3 is a second side view of the archery bow cam.

FIG. 4 is a front view of the archery bow cam.

FIG. 5 is a back view of the archery bow axle cam.

FIG. 6 is a top plan view of the archery bow axle cam; and,

FIG. 7 is a bottom view of the archery bow axle cam.

The broken line showing of aspects of the archery bow cam is included for the purpose of illustrating environment and forms no part of the claimed design.

1 Claim, 5 Drawing Sheets
